UNITED STATES PATENT OFFICE.

JOHN ARCHIE BORLAND, OF MINA, NEVADA, ASSIGNOR OF ONE-EIGHTH TO EARL COVEL, OF CINCINNATI, OHIO.

WRENCH.

995,947.

Specification of Letters Patent. Patented June 20, 1911.

Application filed June 3, 1910. Serial No. 564,765.

To all whom it may concern:

Be it known that I, JOHN ARCHIE BORLAND, a citizen of the United States, residing at Mina, in the county of Esmeralda and 5 State of Nevada, have invented new and useful Improvements in Wrenches, of which the following is a specification.

This invention relates to an improvement in wrenches and is particularly devised as 10 an improvement in that class of wrenches known as the Stilson wrench; the object of the invention being to provide the ordinary stationary jaw of a Stilson wrench with a magazine chamber in which is positioned a 15 movable jaw, the said movable jaw having one of its faces provided with teeth and the chamber or magazine being provided with a yoke having teeth engaging the teeth of the said movable jaw to retain the said jaw 20 within the casing against the tension of a helical spring, the yoke being easily swung out of engagement with the teeth of the sliding jaw so as to allow the said sliding jaw to adjust itself longitudinally in relation to 25 the stationary jaw, thus providing a quick acting wrench which is automatically opened and wherein the sliding jaw may be easily and quickly slid within the casing.

With the above, and other objects in view 30 which will appear as the description progresses, the invention resides in the novel construction and combination of parts hereinafter fully described and claimed.

In the accompanying drawings there has 35 been illustrated a simple and preferred embodiment of the improvement, and in which drawings,

Figure 1 is a side elevation of a wrench constructed in accordance with the present 40 invention. Fig. 2 is a central longitudinal sectional view of the same. Fig. 3 is a transverse sectional view upon the line 3—3 of Fig. 1.

In the accompanying drawings the number 45 1 designates the wrench proper. This wrench comprises what may be termed a stationary clamp 2 provided with the usual jaw 3 and a handle 4.

The numeral 5 designates the movable jaw 50 of the wrench. This jaw 5 has one of its faces provided with a plurality of transversely extending teeth 6 and has its opposite face provided with teeth 7. The jaw 5 is mounted within a suitable casing 8, the 55 latter having a projecting side portion which

is pivotally connected with the stationary jaw 3 as at 9. The side portion comprises what may be termed a housing 10, and one of the walls of the said housing is adapted to be contacted by a flattened spring 11 which is secured to the engaging face of the stationary jaw as at 12. The shank or stationary member 2 is provided with a second flattened spring 13 which is adapted to contact with the face of the casing 8 and to compensate for the pressure of the spring 11 to normally retain the chamber 8 and the jaw 5 carried thereby in a plane substantially parallel to the shank 2. The casing 8 is provided with a transversely extending pin 14, and the shank of the jaw 6 is provided with a longitudinally extending opening 15, the pin being disposed within the said opening and being also adapted to limit the travel of the shank of the movable jaw 70 in either direction. Positioned between the rear end of the shank of the movable jaw 5 and closed face of the casing 8 is a helical spring 16, the same being adapted at all times to exert pressure upon the jaw 5 so as to force the same out of the casing 8.

The numeral 17 designates what I term a yoke. This yoke 17 has its side arms pivotally connected as at 18 with the casing 8 and the said yoke has its connecting member 85 provided with a plurality of teeth 19 which extend through a suitable opening within the casing 8 and which engage the teeth 6 of the movable jaw 5. The yoke 17 has its teeth 19 normally retained in engagement 90 with the teeth 6 of the movable jaw 5 through the medium of a flattened spring 20, which has its free end secured to the top of the casing 8.

Briefly described, the operation of the improved wrench is as follows:—We will suppose that the operator desires to separate the stationary and the movable jaws so as to adjust the same upon a pipe, or the like. The operator will simply grasp the side arm of the yoke 17 so as to raise the teeth 19 out of engagement with the teeth 6. The helical spring 16 exerting pressure between the slideable jaw and the closed end of the casing 8 will force the said jaw the full 95 limit of its slot 15 until contacted by the pin 14. If the distance between the jaws is too great to properly receive the pipe a slight pressure upon the head of the movable jaw 5 will quickly return the said jaw 100 105 110

to its proper position upon the pipe, the teeth 6 being so inclined as to allow the backward movement of the shank of the jaw 5 and the toothed portion 19 of the yoke 17 under the pressure of the spring 20 will prevent the outward movement of the jaw 5 from its casing 8.

Having thus fully described the invention, what I claim as new is:—

- 10 1. A stationary jaw, a casing pivotally connected with the stationary jaw, a movable shank within the casing provided with a jaw, a spring within the casing normally exerting pressure between the shank and the said casing, said shank being provided with teeth, and a spring pressed yoke normally engaging the teeth of the shank.
- 20 2. A stationary jaw, a casing pivotally connected with the stationary jaw, the casing being provided adjacent one of its ends and to the rear of its pivot with a housing, a spring connected with the stationary jaw and engaging the housing, a movable shank within the casing provided with a jaw, a spring within the casing normally exerting pressure between the shank and casing, and a spring pressed yoke normally engaging the shank.
- 25 3. A stationary jaw, a casing pivotally connected with the stationary jaw adjacent one of its ends, said casing being provided with a housing straddling the stationary

jaw, a spring secured to the stationary jaw and engaging the housing, a second spring upon the opposite face of the stationary jaw contacting the rear of the casing, a movable shank within the casing provided with a jaw, a spring within the casing normally exerting pressure between the shank and casing, said shank being provided with teeth, and a spring pressed yoke pivotally connected with the casing and normally engaging the teeth of the shank.

40 4. A stationary jaw, a casing pivotally connected with the stationary jaw, a movable shank within the casing provided with a jaw, said shank being provided with a longitudinally extending opening, a pintle connected with the casing and engaging within said opening to limit the outward movement of the shank, a spring within the casing normally exerting pressure between the shank and casing, said shank being provided with teeth, a yoke having teeth pivotally connected with the casing, and a spring member adapted to force the teeth of the yoke into engagement with the teeth of the shank.

45 In testimony whereof I affix my signature in presence of two witnesses.

JOHN ARCHIE BORLAND.
